(57) **CLAIM**

The ornamental design for a flexible handheld fruit and vegetable holder for peeling and carving, as shown and described.

DESCRIPTION

FIG. 1 is a top perspective view of a flexed embodiment, shown with environment, showing my new design;

FIG. 2 is a top perspective view of a flexed embodiment, thereof;

FIG. 3 is a top perspective view of an unflexed embodiment, thereof;

FIG. 4 is a top plan view of an unflexed embodiment, thereof;

FIG. 5 is a bottom plan view of an unflexed embodiment, thereof;

FIG. 6 is a rear elevation view of a flexed embodiment, thereof; the front elevation view being a mirror image thereof; and,

FIG. 7 is a left side plan of a flexed embodiment, thereof; the right side view being a mirror image thereof.

The broken lines in FIG. 1, showing a fruit, are for the purpose of illustrating environment and form no part of the claimed design.
